US00D700987S

(12) **United States Design Patent**
Nepple et al.

(10) **Patent No.:** US D700,987 S
(45) **Date of Patent:** ** Mar. 11, 2014

(54) **TRAPEZOIDAL LUMINAIRE**

(71) Applicant: **Cooper Technologies Company**,
Houston, TX (US)

(72) Inventors: **Jeffrey Brian Nepple**, Yorba Linda, CA
(US); **Zachary Adam Ingalls**, Denver,
CO (US); **Matthew A. Davis**, Orange,
CA (US); **Dean Grierson**, Westminster,
CO (US)

(73) Assignee: **Cooper Technologies Company**,
Houston, TX (US)

(**) Term: **14 Years**

(21) Appl. No.: **29/450,587**

(22) Filed: **Mar. 19, 2013**

(57) **CLAIM**

The ornamental design for a trapezoidal luminaire, as shown and described.

DESCRIPTION

FIG. 1 is a perspective view of a trapezoidal luminaire, showing our new design;

FIG. 2 is a top plan view thereof;

FIG. 3 is a bottom plan view thereof;

FIG. 4 is a front elevation view thereof;

FIG. 5 is a right-side elevation view thereof;

FIG. 6 is a rear elevation view thereof;

FIG. 7 is a left-side elevation view thereof;

FIG. 8 is a perspective view of another new ornamental design for a trapezoidal luminaire;

FIG. 9 is a top plan view of the trapezoidal luminaire of FIG. 8;

FIG. 10 is a bottom plan view of the trapezoidal luminaire of FIG. 8;

FIG. 11 is a front elevation view of the trapezoidal luminaire of FIG. 8;

FIG. 12 is a right-side elevation view of the trapezoidal luminaire of FIG. 8;

FIG. 13 is a rear elevation view of the trapezoidal luminaire of FIG. 8; and,

FIG. 14 is a left-side elevation view of the trapezoidal luminaire of FIG. 8.

The broken lines shown represent unclaimed subject matter and form no part of the claimed design.

1 Claim, 10 Drawing Sheets
